UNITED STATES PATENT OFFICE.

FRANK R. McBERTY, OF EVANSTON, ILLINOIS, ASSIGNOR TO WESTERN ELECTRIC COMPANY, OF CHICAGO, ILLINOIS, A CORPORATION OF ILLINOIS.

SIGNAL FOR TELEPHONE-SWITCHBOARDS.

No. 804,256.

Specification of Letters Patent.

Patented Nov. 14, 1905.

Application filed July 11, 1902. Serial No. 115,131.

To all whom it may concern:

Be it known that I, FRANK R. McBERTY, a citizen of the United States, residing at Evanston, in the county of Cook and State of Illinois, have invented a certain new and useful Improvement in Signals for Telephone-Switchboards, of which the following is a full, clear, concise, and exact description.

My invention concerns visible signals for telephone-switchboards and means for operating them automatically to call for connection and disconnection.

It consists in a new form of visible signal and circuits for a telephone-switchboard adapted for the operation of signals.

The invention is illustrated in the attached drawings, of which—

Figures 1, 2, 3, and 4 represent the new visible signal, while Fig. 5 is a diagram illustrative of the circuits of the switchboard. Fig. 1 is a side elevation of the signal, the trunnion-lugs being broken away better to display the moving parts. Fig. 2 is a plan thereof. Fig. 3 is a front elevation. Fig. 4 is a rear elevation. Fig. 5 is a diagram representing two subscribers' telephone-lines centering in a switchboard in a central office, together with link conductors for connecting lines and supervisory apparatus in the switchboard.

The signal consists of two magnets, a pivoted armature for each, and a separate pivoted lever or arm carrying an indicator. The two magnets *a* and *b*, each of which may be of the ordinary two-spool form, are carried on a common base-plate *c* of magnetic material, which may also form the support or mounting for the signal. The polar portions of these magnets pass through a support and trunnion-plate *d*. On a spindle or pivot *d'*, passing through lugs in this plate, are mounted the two armatures *a'* *b'* of the two magnets, respectively, and the pivoted indicator-lever *e*. The pivotal support of the armature *a'* is beneath its center of gravity and between the said center and the poles of its magnet, so that the armature tends to fall away from the magnet. The pivot of the armature *b'* is above its center of gravity and farther from the poles of its magnet, so that this armature also tends to fall away from the magnet. By reason of the pivoting of the armatures and indicator-lever upon the same axis there is no rubbing contact in the operation of the arma-

tures to operate the lever, so that a frictionless engagement of said parts is obtained. 55 The indicator-arm *e* is nearly counterbalanced by a small weight at its rear extremity; but the indicator is of such weight that it tends to pass to its lower position. The armature *a'* when resting back from the magnet *a* engages the rear extremity of the indicator-lever, adding its weight to that of the counterbalance, overbalancing the indicator and bringing it into its upper position. Thus when the magnet *a* is excited and attracts its 60 armature the indicator-arm is relieved of the weight of its armature and the weight of the indicator brings it to its lower position. The armature *b'* carries a short lever *b*², engaging the indicator-lever *e* between its pivotal support and the indicator, so that the armature *b'* when attracted forces the indicator to its 65 upper position. The indicator is covered when it lies in its upper position by a plate *f*, but when in its lower position lies before an opening *f'* in the plate, where it is in view of the operator. The armature *b'* is provided with an insulated contact *b*², against which it bears when in its rear position. Thus when the magnet *b* is excited contact with its anvil is 70 broken at the same time that the indicator is restored to its concealed position.

Referring now to the diagram Fig. 5, the substations are furnished with the telephone sets of well-known form, preferably adapted 75 for central-battery transmission and having telephone-switches for closing the circuits during the use of the telephones to control the central-office signals.

The line conductors 1 and 2 are led to the 90 line-contacts of spring-jacks *g* in a multiple switchboard. A visible line-signal of the construction described is provided for each line. The magnet *a* of this signal is constructed of high impedance and resistance and 95 is connected in a permanent branch from the line conductor 1 to one pole of the central battery *h*. A branch to earth or to the other pole of the same battery is normally present, but is controlled at the contact *b*² of the armature *b'*, whereby it is normally closed, but 100 is open when the magnet *b* is excited. The line conductor 2, which is joined by this branch, is connected with the test-rings of the multiple spring-jacks. The magnet *b* of the signal 105 is made of comparatively low resistance—say

of one hundred ohms—and is interposed directly in the line conductor 1 between the junction therewith of the magnet *a* and the spring-jacks of the switchboard. This magnet should be shunted by a condenser or non-inductive resistance to avoid the obstruction of voice-currents.

Pairs of plugs *i* and *i'* are furnished with the usual operator's listening and ringing keys, telephone, and generator. Condensers *k* and *k'* are interposed in the conductors 3 and 4, which constitute the plug-circuit. Associated with each plug is a supervisory signal constructed like the line-signal. The 15 windings of both magnets *a* and *b* may in this case be of one hundred ohms each, but should have high impedance. The winding of magnet *a* of the supervisory signal *l*, which is associated with the plug *i*, is connected in a 20 branch 5, leading from the conductor 4 of the plug-circuit between the plug *i* and the condenser therein to the grounded pole of the central battery *h*. The other magnet *b* of the same signal is connected in another branch 25 from a corresponding point of the conductor 3 of the plug-circuit to the free pole of the same battery. The supervisory signal *l'*, associated with plug *i'*, is similarly connected with the plug-circuit 3 4 with respect to the 30 plug *i'*.

The circuits above described form no part of the present invention, but constitute the subject-matter of a divisional application filed January 20, 1905, Serial No. 241,962.

35 While this apparatus is idle the indicators of all the signals are out of view, being overbalanced by the weight of the armatures *a'*. When a user of the telephone at a substation takes the telephone from its switch and the 40 circuit is closed at the substation, current from the battery *h* flows through the magnet *a* of the line-signal to the substation, returning through the earth branch closed by the armature *b'* of the signal.

45 As before described, relieving the indicator-arm *e* from the weight of the armature *a'* permits the indicator to come into view to indicate the subscriber's call. The operator answers the call by inserting the plug *i* into a 50 spring-jack of the line. Thereby circuit is closed from battery *h* through the magnet *a* of the line-signal to line conductor 1, thence to conductor 4 of the plug-circuit, through the branch 5 to earth. It will be noted that 55 this current traverses not only the magnet *a* of the line-signal, but the magnet *b* of the same signal and the magnet *a* of the supervisory signal associated with the plug *i*. The excitation of the magnet *b* of the line-signal draws 60 up the armature *b'* and forces the indicator back to its concealed position, at the same time breaking the ground branch from line conductor 2. The excitation of magnet *a* of the supervisory signal *l* by drawing up the 65 armature *a'*, and thus relieving the indicator-

arm of that signal from its weight, tends to display the indicator of the supervisory signal; but at the same moment battery *h* finds circuit through the magnet *b* of the supervisory signal to the line conductor 2, thence to 70 the substation, returning to the central office and to earth through the magnet *b* of the line-signal and the magnet *a* of the supervisory signal. Thus both magnets *a* and *b* of the supervisory signal become active simultaneously in answering a call and the indicator remains concealed. On completing connection with the line called for the telephone at the station thereof is found still on its switch, and a different action results. Circuit is 80 formed simultaneously through magnets *a* and *b* of the line-signal of the called line, so that the indicator thereof remains concealed; but as this circuit includes only the magnet *a* of the supervisory signal *l'* the indicator of 85 this supervisory signal is permitted to come into view in condition to indicate the response of the called party.

Taking the telephone from its switch at the called station completes a circuit like that before traced, in which current is supplied for exciting the magnet *b* of the supervisory signal, and the indicator of the signal *l* is thereby hidden.

It will be apparent that the movement of 95 the telephone-switches will control the corresponding supervisory signals, either signal being displayed when the telephone at the station to which it refers is placed on the switchhook. Neither of the line-signals is displayed 100 after connection has been established.

When the indicators of both supervisory signals appear, their indication is taken as a call for disconnection, both telephones having 105 been replaced on their switches.

It will be observed while the apparatus is in its idle or inert condition the test-rings of the multiple jacks are reduced to the potential of the earth, the line conductor 2, with which they are connected, being grounded through 110 the switch-contacts *b'* of the line-signals of their respective lines. When connection is made with any line by means of the plug, however, the battery *h* becomes connected with these test-rings, while at the same time 115 the earth branch from the line conductor 2 is broken. Thereafter the test-rings are electrified to a considerable potential above the earth, so that they shall test busy at the other sections of the multiple switchboard in the 120 usual way.

My invention is defined in the following claims:

1. In a visible signal, the combination with a pivoted weighted indicator-arm, of a weighted 125 armature overbalancing the said arm to conceal the indicator, and a magnet therefor, and a separate armature engaging said indicator-arm to conceal the indicator and a magnet therefor, as described.

2. The combination with a pivoted weighted indicator-arm, said arm being balanced to take a position to display the indicator when free, of an overbalancing weighted armature normally engaging said indicator-arm, to hold the indicator in its concealed position, a magnet adapted to attract said armature to permit the indicator to tilt into a position of display, and a separate pivoted armature adapted to engage said indicator-arm to act thereon in the same direction as the overbalancing-armature, as described.

3. In combination, in a visible signal, the weighted indicator-arm *e*, the overbalancing-armature *a'* and the magnet therefor, the pivoted armature *b'* and the lever *b³* thereof adapted to engage the indicator-arm, and the magnet *b*, as described.

4. The combination with a pivoted indicator-lever carrying an indicator on its long arm,

said arm being balanced to take a position of display when free, the overbalancing-armature bearing upon its short arm when unattracted, and the magnet for moving said armature, a pivoted armature adapted, when attracted, to engage the long arm of said lever, and a magnet for acting upon said last-mentioned armature, as described.

5. In combination, the pivoted indicator-lever *e*, the overbalancing-armature *a'*, and the pivoted restoring-armature *b'*, said armatures and lever being pivoted in the same axial line, whereby a frictionless engagement is obtained.

In witness whereof I hereunto subscribe my name this 13th day of June, A. D. 1902.

FRANK R. McBERTY.
